UNITED STATES PATENT OFFICE.

VITUS HEMBACHER, OF FISCHACH, GERMANY.

FIRE-ESCAPE.

SPECIFICATION forming part of Letters Patent No. 542,641, dated July 16, 1895.

Application filed October 18, 1894. Serial No. 526,280. (No model.)

To all whom it may concern:

Be it known that I, VITUS HEMBACHER, a citizen of Germany, residing at Fischach, in the Kingdom of Bavaria, Germany, have invented certain new and useful Improvements in Fire-Escapes; and I do hereby declare the following to be a full, clear, and exact description of the invention, such as will enable others skilled in the art to which it appertains to make and use the same.

My invention relates to improvements in life-saving devices or fire-escapes.

The object of my invention is to produce a device designed to be used for rescuing one's self or other persons, or for saving household furniture and the like during fires and similar dangers.

The invention consists in such features, details of construction, and combination of parts as will first be described in connection with in the accompanying drawings, and then particularly pointed out in the claims.

In the drawings, Figure 1 is a longitudinal central section of a device embodying my improvement. Fig. 2 is a similar view taken at right angles to Fig. 1. Fig. 3 is a view illustrating the manner of using the device.

Referring to the drawings, *a* are two iron tracks, between which, at one end, is a roller *c*, movable upon a fixed axis *b*. At the other end the tracks are joined by a cross-pin *d*, provided with an eye engaged by a hook *e*. Between the roller *c* and the tracks *a* are located two sliding tracks *f* of the same width as the tracks *a*, these sliding tracks *f* being provided with central slots, through which pass studs *g*, secured in the tracks *a*, and provided with heads, as shown.

The tracks *f* are joined at the middle by an axle *h*, upon which is revolvably mounted a shifting-roller *c'*, the axle *h* being out of the central longitudinal axes of the sliding tracks *f*.

As the tracks *f* are free to move, the roller *c'* can be brought nearer to or farther from the roller *c*. The rescuing-rope *i* passes over the rollers *c c'* in S-fashion, as shown in dotted lines in Fig. 2. The end of the rope which passes over the lower roller is attached to a hook, which may be fastened to a suitable place, for instance, to the window-frame, as shown in Fig. 3, while the longer end or fall,

after passing over the upper roller, reaches to the ground in the street or yard, &c.

The article *l*, Fig. 3, to be removed from the building is secured to the hook *e* and the hanging end of the rope *i* is held by a person on the ground.

The weight of the load causes the lower roller *c'* to be pressed against the upper roller *c*, thus tending to clamp the rope *i* between the two rollers, whereby the load will not descend too rapidly. The rate at which the load descends may be regulated by the amount of strain upon the lower end of the rope, a great strain tending to crowd the rollers together and thus check the descent of the load, while a slight strain, or none at all, permits the rollers to separate, whereby the load falls rapidly. By this means the danger of injuring the article by too rapid a descent or by striking the ground is avoided. When the load arrives at the bottom the two rollers may be separated, whereupon the rope can be readily withdrawn.

In rescuing persons the hook *e* is hooked into a ring on a belt placed about the waist of the person, whereby such person, after swinging out from the window, may be lowered to the ground in the same manner as the weight described above, so that he will not descend too rapidly or strike the ground too hard.

If a person desires to rescue himself from a building with an apparatus constructed in accordance with my invention he takes hold of the lower part of rope *i*, and after securing himself to the hook *e*, in any suitable manner, lowers himself by alternately releasing his hold of the rope with one hand and taking a fresh hold again a little farther down, just as if he were descending hand over hand down the rope. In doing this, as his down-climbing action is more or less rapid, and as he allows the rope to pass through his hands more or less quickly, the descent will be more or less rapid, for the reason that the pressure upon the two rollers will be greater or less.

The apparatus may be provided with a ring in place of the hook *e* and instead of a belt may have a basket attached to it.

On account of its simplicity this apparatus can be used by unskilled persons and can also be used in places where other apparatus could not be used.

The chief advantage of the apparatus lies in its practical construction and simplicity, on account of which the article or person to be rescued itself regulates the speed of descent

5 to the earth. During the descent a slight pull on the rope will cause a halt. In saving one's self or in saving others only a single person is necessary. The device is suitable not only for the use of firemen, but also for the inmates 10 of houses.

Having thus fully described my invention, what I claim as new, and desire to secure by Letters Patent, is—

15 1. The combination, with a pair of sliding tracks, each having an upper and a lower slot, an axle fixed between the said sliding tracks, and a roller mounted on the axle, of a pair of tracks outside the slotted tracks, an axle fixed in the ends of the said outer tracks and passing through the upper slot in the slotted tracks, a roller mounted on said axle, a pair 20 of studs passing through the lower slots and

fixed in the outer tracks, and a rope passing under the second roller, over the first roller and thence to the ground, substantially as set forth.

2. The combination, with a pair of tracks, an axle connecting said tracks at the upper ends, a cross piece connecting the lower ends of said tracks and provided with an eye, a roller journaled on the axle, and a hook device engaging the eye in the cross piece, of a pair of slotted sliding tracks, a roller journaled therein, and a pair of studs passing through the slots in the sliding tracks and 35 fixed into the other tracks, substantially as set forth.

In testimony whereof I affix my signature in presence of two witnesses.

VITUS HEMBACHER.
